UNITED STATES PATENT OFFICE.

EDWARD I. PEARSON, OF LEIPSIC, OHIO, ASSIGNOR TO THE TEMCO ELECTRIC MOTOR COMPANY, OF LEIPSIC, OHIO, A CORPORATION OF OHIO.

VIBRATOR.

1,177,800.

Specification of Letters Patent. Patented Apr. 4, 1916.

Application filed March 15, 1915. Serial No. 14,562.

To all whom it may concern:

Be it known that I, EDWARD I. PEARSON, a citizen of the United States, and a resident of Leipsic, in the county of Putnam 5 and State of Ohio, have invented a certain new and useful Vibrator; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 My invention relates to electric vibrators for producing pulsations of high potential current.

It is particularly adapted for use in producing sparks at the terminals of the spark 20 plug in an engine cylinder.

By my invention an electric vibrator is produced which is exceedingly efficient and durable and one that is easily adjusted and which will retain its adjustment in the operation 25 thereof.

The vibrator is so constructed that the vibratory or pulsating current will be produced at a very little loss, requiring the consumption of a very little energy, and yet 30 one wherein the breaks will be perfect and complete and very rapid.

The invention may be contained in many forms of electromagnetic structures usable for different purposes, all of which come 35 within the purview of my claims herein-after appended.

To show the practicability of my invention I have selected one of such constructions as an example and shall describe it 40 hereinafter. The construction selected is illustrated in the accompanying drawings.

In the drawings Figure 1 is a top view of a vibrator containing my invention. Fig. 2 is a vertical, sectional view taken centrally through the structure shown in Fig. 1. Fig. 3 illustrates an adjusting screw for adjusting the vibrator arm or reed and is shown enlarged in order that it may be more clearly illustrated.

50 Fig. 1, Fig. 1, is the base on which the parts of the structure containing my invention are mounted. The base may be formed of any insulating material, such as, fiber or stone or hardened insulating composition 55 which will prevent short-circuiting of parts

of the device. The binding posts, contacts and other parts are clamped to the base 1. An iron-clad magnet 2 is located in a shell 3. The shell 3 is provided with a flange 4 and a threaded portion 5. A rim nut 6 60 may be threaded over the threaded portion 5 and so as to clamp the base 1 and thus lock the shell 3 and the magnet 2 in position in the base 1. The magnet is also provided with the core 7 which may be suitably 65 secured to the shell 3. A vibrating reed 10 extends from a supporting block 11 over the magnet 2. The reed 10 has an arm 12 which terminates in a disk 13. The disk 13 covers the upper end of the shell 3 and 70 so as to complete the magnetic circuit from the shell 3 to the core 7. It reduces as much as possible the reluctance of the magnetic circuit of the magnet and affords an efficient armature of small mass which gives 75 small inertia to the reed and permits rapid and yet responsive movements to the reed and the contact carried thereby.

The reed 10 is secured to the block 11 by means of the screw 14. The block 11 may 80 be secured in position on the base 1 by means of the nuts 8 and the bolts 9 which clamp the block 11 to the base 1. The reed is provided with an eyelet 15 having a slot 16 connected therewith. A bolt 17 85 having a channel 18 formed in its head 19 may be inserted through the eyelet 15 which is large enough to permit the head 19 to pass through. The head 19 of the bolt may then be slipped along the reed 10 so that 90 the sides of the slot 16 will enter the channel 18 and the reed will thus be held in a position parallel to the base 1 when the bolt is threaded into the block 11. The reed 10 may thus be adjusted by screwing the 95 bolt 17 into the block 11 while the reed 10 will be maintained at all times in a position parallel to the base whatever adjusted position it may be placed in by the bolt 17. If the reed 10 is raised above the block 11 the reed 100 will be slightly bent at a point between the bolt 17 and the bolt 14 and the reed will be bound in the channel 18 so that the bolt 17 will be held in position by the tension 105 of the reed 10. It is requisite that the reed 10 and its disk 13 be positioned very close to the upper end of the magnet 2 and, particularly, very close to the upper end of the shell 3 and thus be maintained in a position 110 which is parallel to the plane of the upper

edge of the shell 3. The side walls of the channel 18 will thus hold the reed 10 in a position parallel to the base 1 and the disk 13 parallel with the plane of the upper edge 5 of the shell 3.

An arm 20 is supported on a bridge 21 which extends across two posts 22 located on opposite sides of the reed 12. The arm 20 and the bridge 21 are held in position by 10 means of the nuts 23 which thread upon the bolts 24 which extend up through the posts 22. The posts also are clamped to the base 1 by means of the nuts 23 and the bolts 24. The arm 20 is slightly stepped at 25, at its 15 point of connection with the bridge 21. A thin metal strip 26 is riveted to the bridge 21 by means of the rivets 27 and it is loosely riveted to the arm 21 by the rivet 28, it being made straight it is disposed in spaced 20 relation with respect to the arm 20 which gives room for some flexure to the outer end of the strip 26. The outer end of the strip 26 and the outer end of the reed 10, that is, the outer edge of the disk 13 are 25 provided with platinum contact points 29 where the electric circuit 45 from a suitable source is completed through the magnet and through an induction coil or other device to which the vibrator may be connected, 30 and also where it is broken.

The arm 20 is adjusted in its position so as to bring about a proper adjustment between the contact points 29 by means of the bolt 35 which is provided with the gnarled 35 flange nut 36 which may be threaded upon the bolt 35 to force the arm 20 toward the base 1 and consequently to place the contact points 29 nearer together. The reed 10 may also be raised by means of the bolt 17 to 40 bring the contact points nearer together. In order to hold the nut 36 from turning when it is in such position that it would very loosely press upon the arm 20 a spring 37 is provided which is located about the bolt 45 35 and between the nut 36 and the base 1. The arm 20 is broadened at 32 to prevent bending except at the necks 33.

Strips of metal 40 and 41 may be located intermediate the heads of the bolts 9 and 50 24. They may be located in channels 42 and

afford a means for ready contact with a suitable contact located beneath the base 1 as may be desired.

The construction selected and described may be greatly varied in the arrangement 55 and manufacture of its parts and in the substitution of elements having equivalent functions and such modifications may be used for many varied purposes and still contain the invention. 60

Having thus described my invention, what I claim as new, and desire to secure by Letters Patent, is,—

1. In an electric vibrator, a reed, a magnetic means for operating the reed, means for adjusting the reed and maintaining it in a parallel relation with respect to its different positions of adjustment, an elastic arm, contacts supported by the arm and the reed, and means for locking one end of the 70 arm in position and means for flexing the arm to adjust the contacts with respect to each other. 65

2. In an electric vibrator, the combination of a reed having an eye and a slot communicating with the eye, and a channeled headed bolt adapted to be inserted in the eye and so as to engage opposite sides of the reed at opposite edges of the channel. 75

3. In an electric vibrator, a reed, an electromagnetic means for operating the reed, the reed having an eye and a slot communicating with the eye, a channeled headed bolt adapted to be inserted through the eye and slipped along the channel to engage opposite sides of the reed at opposite edges of the slot, an arm, means for locking one end of the arm, a strip of metal secured to the arm, a portion of the strip being located in spaced relation with respect to the arm, 90 the strip and the reed having contacts, and means for flexing the arm to adjust the contacts. 85

In testimony whereof, I have hereunto signed my name to this specification in the 95 presence of two subscribing witnesses.

EDWARD I. PEARSON.
